UNITED STATES PATENT OFFICE.

ISRAEL H. HENRY, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 16, 1924. Serial No. 743,920.

To all whom it may concern:

Be it known that I, ISRAEL H. HENRY, a citizen of the United States of America, residing at East Orange, in the county of Essex and State of New Jersey, have invented certain new and useful Improvements in Telephone-Exchange Systems, of which the following is a full, clear, concise, and exact description.

10 This invention relates to telephone exchange systems and more particularly to systems in which automatic switches are employed in the establishment of connections.

In automatic telephone systems where 15 connections are established under the control of register senders, these senders are associated with all calling subscribers' lines during the establishment of a connection. In the case of certain lines it is necessary 20 that a coin be deposited by the subscriber before a complete connection can be established. In the case of these lines it has been customary to associate a register sender with the line a second time in order to collect or 25 refund this coin. Since a register sender is a complex and expensive organization it is desirable to reduce the time during which it is employed in connection with each call, in order that the total number necessary 30 to serve an exchange may be reduced to the least number consistent with good service.

It is an object of the present invention to provide means for collecting and refunding a coin deposited at a subscriber's substation 35 independent of the register sender.

40 A feature of the invention lies in the provision of a plurality of mechanisms any one of which may serve to collect or refund the coin deposited in connection with a particular call.

Another feature of the invention lies in causing all idle coin control mechanisms to 45 hunt for an extended line at the substantiation of which a coin is to be collected or refunded.

Other features of the invention will be 50 evident from a consideration of the following description in connection with the drawings and appended claims.

55 In the drawings, Fig. 1 shows one of a group of subscribers' lines, together with the trip circuit serving the group.

Fig. 2 shows a start circuit serving a plurality of groups of lines.

Fig. 3 shows a line finder-district selector 55 circuit for extending the line.

Fig. 4 shows one of the plurality of link circuits serving the subgroup including the line 100.

Figs. 5, 6, 7, 8, 9, 10 and 12 show the circuits of the register sender adapted to be selected by the link circuit of Fig. 4 and to control the switches in their selective action.

Fig. 11 shows a diagrammatic form 65 switches necessary to extend the connection from the district selector of Fig. 3.

Fig. 13 shows one of a plurality of coin control circuits embodying in part the present 70 invention.

Fig. 14 is a diagram showing the manner in which the several figures of the drawing should be arranged to show the complete circuits of the invention.

Before proceeding with the detailed description a brief statement of the operation of the circuits may be desirable.

Subscribers' lines such as line 100 are connected to multiple terminals appearing before a plurality of line finders. These 80 multiple terminals are arranged in a plurality of groups each group being served by a separate brush set on each finder and each group being divided into two subgroups. A trip circuit is provided individual to each group; a start circuit is provided for all the groups of lines served by the group of line finders; and a plurality of link circuits are provided for each group of lines and line finders. The line finders 90 and link circuits are divided into two subgroups and each such subgroup normally serves calls in the corresponding subgroup of lines. The arrangement is such that, except when all link circuits are busy, a particular link circuit will be in readiness to serve a call and will be connected by its district finder to an idle line finder.

When a call is initiated by a subscriber in a particular group, the trip circuit individual to the group, and the start circuit are taken for use by that line and means are provided for preventing the extension of a call in the other subgroup of the group or in any other group until the line finder has 105 been started in search of this calling line. Means are also provided for preventing the extension of a second call in this group un-

til after simultaneous calls in other groups have been taken care of. The operation of the start circuit causes the line finder associated with the link circuit allotted for use, 5 to hunt for the calling line and also causes the link circuit to hunt for an idle sender. As soon as a particular link is taken for use with a call the next link is allotted to serve the next incoming call in the particular sub- 10 groups which they serve. As soon as a brush set on the line finder has been tripped the start circuit will be freed to permit the extension of calls in other groups. As soon as the line has been found the trip circuit of the 15 group is freed by the line finder to extend another call in the same group provided no call is awaiting extension in another group. As soon as selections are completed the sender and link circuit are released by the district 20 selector circuit and the link circuit immediately hunts for another idle district.

Substation 100 is one at which a coin box is located for the purpose of requiring pre-payment for calls. Substations of this type 25 are served by register senders which are arranged to prevent the completion of a connection unless the required coin is deposited in said coin box.

When the subscriber at substation 100 removes his receiver from the switchhook a 30 circuit is closed for line relay 101 extending from battery through that relay, inner contact of relay 102 over the subscriber's loop to ground at the outer contact of relay 102. 35 Relay 101 operates and closes a circuit from battery, resistance 104, through the winding of relay 103 to ground at the outer contact of relay 101.

The operation of relay 103 closes a circuit 40 from battery, resistance 105 to ground at the outer right contact of relay 103. This circuit is in shunt of the winding of relay 106, which relay serves the second subgroup of the group to which line 100 belongs, thus 45 preventing the extension of a call from that subgroup, while the trip circuit is in use with line 100. The operation of relay 103 also closes a circuit from battery, through the winding of relay 200, conductor 133, outer left contact of relay 107, outermost 50 left contact of relay 103 to ground. In addition relay 103 closes a circuit from battery, over the back contact of relay 201, right winding of trip relay 108, inner left 55 contact of relay 107, innermost left contact of relay 103, left contact of relay 109 to ground.

Relay 108 operates in this circuit and 60 closes a locking circuit for itself from ground, right contact of relay 109, left winding and inner left contact of relay 108 over the inner left back contact of the trip relays of the other groups of lines, conductor 129, right winding of start relay 201 to battery. Relay 201 operates in this circuit. 65

A circuit is now closed for relay 110 extending from battery through the winding of relay 110, right contact of relay 108, conductor 128, to ground at the outer right contact of relay 201. Relay 110 locks in an obvious circuit to ground at the left back contact of relay 109. Relay 108, together with relay 103 closes a circuit from the outer contact of relay 110, outer left front contact of relay 108, inner right contact of relay 103, conductor 131, left back contact of relay 202, outer left back contact of relay 203, conductor 206, upper contact of cam 401, upper contact of cam 402, brush 461 and its associated terminal, conductor 378, lower left and upper right contacts of cam 301, winding of relay 302, to battery, the line finder of Fig. 3 having been assumed to have been allotted for use by the switch 460 and the sequence switch 300 therefore 80 standing in position 2.

The operation of relay 108 also closes a circuit from ground over its outer right contact, through the winding of the trip magnet 303, serving the group in which line 100 appears on the line finder frame, to battery. Relay 110 upon operating closes a circuit from battery, through the left winding of relay 109, left winding of relay 107, outer contact of relay 110 to ground. Relay 107 operates and locks through its right winding and inner right contact to the contact of relay 200.

The operation of relay 302 closes a circuit 100 from battery, through the winding of up-drive magnet 304, inner left contact of relay 302, upper left contact of cam 364, left front contact of relay 302 to ground.

Under the control of the updrive magnet 304 the line finder shaft is moved upwards. 105 Due to the operation of the trip magnet 303 the set of brushes serving the group of lines to which line 100 belongs is tripped. When the magnet leaves the tripping zone a circuit is closed from ground over brush 307, through commutator segment 305, upper contacts of cam 306, outer left normal contact of key 204, inner right contact and right winding of relay 201 to battery. Relay 201 110 is held operated in this circuit but the circuit through the locking winding of relay 108 is shunted and that relay releases, in turn releasing the trip magnet 303. As soon as brush 307 leaves segment 305 the circuit of relay 201 is opened and that relay releases again connecting battery to the operating windings of relay 108 and the corresponding relays in other trip circuits, so that subsequent calls may be served. 115

Relay 302 closes a locking circuit for 125 itself over its inner right contact, lower left contact of cam 308, back contact of relay 320, commutator segment 321, brush 322, to ground, which is closed as soon as the line finder shaft moves upward. Relay 302 also 130

closes a circuit from battery, over the inner left contact of relay 205, right winding of relay 203, conductor 207, left contacts of cam 403, brush 462, and its associated terminal, conductor 379, lower right contact of cam 311, outer left front contact of relay 302 to ground. The operation of relay 203 removes ground from conductor 206 thus preventing the start of another line finder 5 until the brushes are tripped. Relay 203 locks in a circuit from battery, over the outer left contact of relay 205, left winding and outer left front contact of relay 203, left back contact of relay 202, conductor 15 131, inner right contact of relay 103, outer left contact of relay 108, outer contact of relay 201 from battery, left contact and left winding of relay 201, inner right contact of relay 203 to ground. The circuits just traced are established before relay 108 is released by the shunting action of commutator segment 305. As soon however as 20 relay 108 deenergizes it opens the locking circuit of relay 203, restoring the start circuit to condition to serve subsequent calls. When relay 302 operates it also closes a 25 circuit from ground through its outer left front contact, lower right contact of cam 311, conductor 379, brush 462, and its associated terminal, right contact of cam 404, upper left contact of cam 405, right winding of relay 406, winding of relay 407, upper 30 left contact of cam 408, upper right contact of cam 409, resistance 410 to battery. Relays 406 and 407 operate, relay 406 closing a locking circuit for itself and relay 407 from battery, through resistance 410, upper right contact of cam 409, upper left contact of cam 408, winding of relay 407, right winding of relay 406, contact of cam 411, contact of relay 406 to ground. Relay 407 closes a circuit from battery, through the 35 winding of sequence switch magnet 400, upper contact of cam 412, contact of relay 407 to ground. Magnet 400 operates advancing the link circuit sequence switch to position 2. 40 In position 2 ground is connected from the right contact of cam 415 to brush 466 and its associated contact, conductor 375, lower left contact of cam 312, lower right contact of cam 313, right winding of relay 314 to battery. Relay 314 operates, but performs 45 no function until the calling line has been found. Ground from the front contact of relay 406 is also extended over the contact of cam 411, upper left contact of cam 405, upper right contact of cam 404, left contacts of cam 403, conductor 207, right winding of relay 203, inner left contact of relay 205 to battery, holding relay 203 operated until the link circuit is moved out of position 1. 50 When the link circuit arrives in position 2

relays 406 and 407 release. The release of relay 407 completes a circuit from ground at the back contact of relay 407, upper right and lower left contact of cam 405, winding of magnet 487 to battery. Magnet 487 operates and closes an obvious circuit for magnet 488. Magnet 488 is the rotary magnet for sender sector switch 480 and causes the switch to rotate in search of an idle sender. 75

An idle sender is characterized by the connection of battery, through a 150 ohm resistance, such as resistance 501, to conductor 502 and its corresponding terminal in the set engaged by brush 483. With the link circuit sequence switch in position 2 ground is connected over the upper right contact of cam 421, through the left winding of relay 406, lower contact of cam 413, right winding of relay 406, winding of relay 407, lower contact of cam 401, lower right contact of cam 402 to brush 483. 80

When brush 483 encounters a terminal corresponding to an idle sender, to which battery is connected, relay 406 operates, short circuiting its left hand winding over its contact and the contact of cam 411, permitting relay 407 to operate in series with the right hand winding of relay 406. The operation of relay 407 opens the circuit of magnet 487 and closes a circuit from battery through the winding of sequence switch magnet 400, upper contact of cam 412, front contact of relay 407 to ground advancing the link sequence switch to position 3. 90

In position 3 a circuit is prepared extending from ground through the right and middle windings of relay 503, inner left contact of relay 504, right back contact of relay 505, conductor 506, brush 484 of sender selector 480, lower left and upper right contacts of cam 408, brush 464 of district finder 460 to conductor 315, left contact of cam 316, right winding of relay 317 to battery, which circuit is not completed until the district circuit reaches position 3. 105

In the meantime the line finder shaft continues to move upwards until it reaches the terminals corresponding to the calling subscriber's line. When these terminals are encountered a circuit is completed from battery, through the right winding of relay 109 and resistance 111 in parallel, inner front contact of line relay 101, conductor 114, terminal 380, brush 381, upper left and lower right contacts of cam 318, winding of relay 320 to ground. Relay 320 operates and closes a circuit in shunt of its winding through resistance 319, right front contact of relay 320, commutator segment 321, brush 322 to ground. Relay 109, which is marginal, is so adjusted as not to operate in the circuit previously traced in series with relay 107 or in the circuit traced for the winding of relay 320. With resistance 115 120 125 130

319 in parallel with relay 320 relay 109 operates and locks through its left hand winding, left winding of relay 107, outer left contact of relay 110 to ground. The 5 operation of relay 109 opens the locking circuit of relay 110 and relay 110 releases after an interval due to the fact that it is slow to release. Relay 320 opens the locking circuit of relay 302 and that relay releases as soon as brush 310 encounters an insulating segment of centering cam 309.

The release of relay 302 opens the circuit of updrive magnet 304 and stops the line finder on the calling subscriber's line. It 15 also connects battery through resistance 323 and its outer right back contact, upper contacts of cam 324, inner back contact of relay 387, resistance 325, brush 326, and terminal 327, over conductor 112, winding of cut-off 20 relay 102 to ground. Relay 102 operates and releases line relay 101 removing the calling condition from terminal 380 and opening the circuit of relay 109 which releases. The release of relay 101 permits relay 103 to release and also opens the circuit of relay 320. The connection of battery with terminal 327 marks terminal 113 and the other multiple terminals of calling line 100 in the terminal banks of final selectors with reduced battery potential to render the line busy at such final selectors. The release of relay 302 also closes a circuit from battery through the winding of sequence switch magnet 300, upper left contact of 35 cam 328, left front contact of relay 314, left back contact of relay 302 to ground. Sequence switch 300 is advanced in this circuit to position 3.

When sequence switch 300 leaves position 40 2 the circuit of relay 314 is opened and that relay releases. When the sequence switch 300 reaches position 3, the previously traced circuit for relays 503 and 317 is completed. Relay 317, being marginal does not operate 45 at this time. Relay 503 operates and closes an obvious circuit for relay 507 which in turn closes a circuit from battery, through resistance 508, winding of relay 509, outer left front contact of relay 507 to ground. 50 Relay 509 operates and locks over its inner right front contact. Relay 507 closes a circuit for relay 510 from battery, winding of relay 510, conductor 534, to ground, at the inner left front contact of relay 507. It also 55 closes a circuit from battery, through the winding and right normal contact of relay 601, normal contact of brush 602 of timing switch 600 and thence to ground over conductor 534 to the inner right front contact of relay 507. The operation of relay 510 60 closes an obvious circuit for relay 511 which in turn closes a circuit through the left winding of relay 512. The operation of relay 601 closes a circuit from battery, through the winding of relay 603, normal

terminal and brush 604 of switch 600, inner left front contact of relay 601 to ground. Relay 603 operates and closes a circuit through the winding of stepping magnet 605, and its back contact, front contact of 70 relay 603, brush 604 and its normal terminal, to ground at the inner left contact of relay 601. Magnet 605 operates and steps switch 600 to its first terminal. The further operation of the timing switch 600 will be described later.

The operation of relay 512 opens the circuit previously traced from battery, through resistance 501, to relays 406 and 407 and these relays release. The release 80 of relay 407 closes a circuit from battery, through the winding of sequence switch magnet 400, lower right contact of cam 412, back contact of relay 407 to ground. Sequence switch 400 is advanced to position 4 from which position it is moved to position 5 by means of ground over the lower left contact of cam 412.

In position 5 of the link sequence switch 400 the dialing leads and the fundamental circuit leads are cut through directly from the district circuit to the sender circuit. The dialing circuit may be traced from battery, through the left winding of relay 606, conductor 637, left back contact of relay 1200, 90 left back contact of relay 1201, conductor 1202, sender selector brush 485, and its corresponding terminal, lower contacts of cam 414, district finder brush 465 and its corresponding terminal, conductor 382, lower left contact of cam 329, winding of relay 330, right back contact of relay 317, line finder brush 331, terminal 332, conductor 116 through the subscriber's substation, conductor 117, terminal 333, brush 334, outer 95 left back contact of relay 317, lower contact of cam 335, conductor 375, brush 466, and its associated terminal, lower left contact of cam 415, brush 486, and its associated terminal, conductor 1203, right back contact of relay 1204, right back contact of relay 1200 to ground.

In position 5 of the link circuit sequence switch 400, relays 406 and 407 are connected in a circuit extending from brush 484, left contacts of cam 408, winding of relay 407, right winding of relay 406, upper contact of cam 413, to brush 464. The circuit of these relays is extended from these brushes as will be later described. When the dialing circuit above traced is completed, relay 606 operates and closes a circuit from battery, through the winding of relay 610, front contact of relay 606, conductor 639, inner right back contact of relay 515 to ground. Relay 610 operates and closes a circuit from battery, through the winding of relay 609, right front contact of relay 610, conductor 638, upper left contact of cam 516 to ground. As soon as relay 609 115 120 125 130 135

operates the dialing tone circuit is completed as follows: From source of tone 607, right winding of relay 606, normal terminal and brush 804 of register steering switch 800, outermost left contact of relay 609, conductor 618, lower contact of cam 514, conductor 534, to ground at the inner left front contact of relay 507.

Due to the closure of this circuit a tone is induced in the left winding of relay 606 and over the dialing circuit to the receiver of the subscriber's telephone to indicate that dialing may be started. The subscriber now dials the number of the wanted subscriber.

Dialing takes place, and the registers 810, 820, 1000, 1010, 1020, 1030 and 1040 are positioned as described in the copending application of O. H. Kopp, Serial No. 20 743,919 filed Oct. 16, 1924. As soon as registers 810 and 820 are set, translator 830 is positioned to control various selections, after which class sequence switch 950 is positioned. As soon as the translator is 25 positioned sequence switch 500 is advanced to position 2.

With the sequence switch 500 in position 2 the fundamental circuit is completed from battery, through the right winding of relay 314, lower right contact of cam 313, lower contact of cam 312, conductor 378, brush 461 and its associated terminal, upper right and lower left contact of cam 402, brush 481 and its associated terminal, right 35 back contact of relay 504, right contact of cam 701, winding of stepping relay 702, back contact of relay 703, left winding of relay 704, left contact of cam 705, inner right contact of relay 620, middle left contact of relay 621, resistance 623 to ground, relays 620 and 621 having energized upon the setting of the translator switch 830 in the manner set forth in the aforementioned application of O. H. Kopp. Relays 314 40 and 702 operate in this circuit but relay 704 is polarized and does not. Relay 314 locks through its outer right front contact, lower left contact of cam 313, lower right contact of cam 312, to the fundamental 45 circuit as previously traced. Relay 314 in operating also closes a circuit from battery through the winding of sequence switch magnet 300, upper left contact of cam 328, left front contact of relay 314, left back contact of relay 302 to ground. Magnet 300 energizes in this circuit and advances the sequence switch to position 4.

In position 4 the energizing circuit for relay 314 is opened but the locking circuit is 50 maintained closed. At the same time a parallel circuit is prepared from the outer right front contact of relay 314, lower left contact of cam 313, upper right contact of cam 312, commutator segment 337, brush 55 338, upper left contact of cam 339 to ground.

In position 4 relay 314 closes a circuit from battery, through the winding of updrive magnet 340, upper right contact of cam 341, left front contact of relay 314, back contact of relay 302 to ground. The updrive magnet energizes in this circuit and causes the district selector switch shaft to move upward in a brush selecting movement. Each time that brush 338 makes contact with a conducting segment of strip 337 the parallel circuit above traced is completed, in which circuit relay 314 is held operated and the stepping relay of the sender shunted.

When the fundamental circuit above traced was closed and stepping relay 702 operated, it closed a circuit from battery, inner left contact of relay 621, left contact of cam 519, winding of the No. 3 counting relay, (assuming that the translator has been set in position to select the fourth brush on the district selector) back contact of the No. 3' counting relay, conductor 706, translator brush 855 and its corresponding terminal, right contacts of cam 707, inner left back contact of relay 708, left contact of cam 520, 80 contact of relay 702, lower left contact of cam 518 to ground. The No. 3 counting relay operates in this circuit and locks through the winding of the No. 3' counting relay, 85 front contact of the No. 3 counting relay, upper right contact of cam 709 to ground. The No. 3' counting relay does not operate at this time since its winding is shunted by the energizing circuit of the No. 3 counting relay. When, in its upward movement, brush 338 of the district selector encounters the first conducting segment of commutator strip 337, stepping relay 702 is shunted and deenergized, opening the above traced circuit for the No. 3 counting relay permitting the No. 3' counting relay to operate in the locking circuit of the No. 3 counting relay.

The energization of the No. 3' counting relay connects conductor 706 through the back contact of the No. 2' counting relay to the winding of the No. 2 counting relay and thence to battery. When brush 331 encounters an insulating segment the shunt is removed from relay 702 and that relay again energizes closing the circuit from ground to conductor 706 causing the energization of the No. 2 counting relay. As the district selector switch shaft continues upward and brush 338 engages the insulating and conducting portions of the commutator strip 337, stepping relay 702 is alternately deenergized and energized and the counting relays successively operated. When brush 338 reaches the fourth conducting segment and stepping relay 702 deenergizes for the fourth time, the 0' counting relay operates in parallel with relay 703 and in series with the No. 0 counting relay. The operation of relay 703 opens the fundamental circuit and permits the release of relay 314 as soon as 100 105 110 115 120 125 130

brush 338 leaves the conducting segment. The operation of the 0' counting relay closes a circuit from battery through the winding of sequence switch magnet 700, right contact 5 of cam 710, left back contact of relay 708, front contact of the 0' counting relay to ground at the inner back contact of relay 711. Sequence switch 700 is energized in this circuit and advances the sender sequence switch to position 3. As soon as sequence switch 700 leaves position 1 1/4 the locking circuits of all operated counting relays are opened, releasing such relays. The release of relay 314 as previously described 15 opens the circuit of up-drive magnet 340 and closes a circuit from battery, through the winding of sequence switch magnet 300, right contacts of cam 342, outer left back contact of relay 314, back contact of relay 20 302 to ground, in which circuit the sequence switch is advanced to position 5.

With sequence switch 300 in position 5 and sequence switch 700 in position 3 the fundamental circuit is again closed from 25 battery, through the right winding of relay 314, lower right contact of cam 313, lower right contact of cam 312, conductor 378, thence as traced previously, outer right back contact of relay 504, right contact of cam 701, winding of relay 702, contact of relay 703, left winding of relay 704, left contact of cam 705, innermost right contact of relay 620, middle left contact of relay 621, resistance 623 to ground. Relays 314 and 702 operate in this circuit as before. Relay 314 locks as previously described and closes the previously traced circuit for sequence switch 300 in which circuit the sequence switch advances to position 6. The 40 operation of stepping relay 702 closes a circuit from battery, right contact of cam 519, through the winding of the No. 1 counting relay (assuming that the translator is set in position to cause the selection of the second group of outgoing trunks served by the fourth set of brushes) back contact of the No. 1' counting relay, conductor 712, translator brush 854, lower right and upper left contact of cam 707, inner right back contact of relay 708, left contact of cam 520, contact of relay 702, lower left contact of cam 518 to ground. In 45 positions 5 to 7, inclusive, of sequence switch 300 trip magnet 343 is energized in a circuit extending from battery through its winding, to ground at the lower right contact of cam 336. When the sequence switch arrives in position 6 updrive magnet 340 is again energized and the district selector switch shaft is moved upward in a group selecting movement. Due to the energization 50 of trip magnet 343 and the positioning of the district selector in accordance with the brush selecting operation just described

the fourth brush set is tripped and moved 65 over its corresponding terminals.

As in the case of brush selection a shunt circuit is prepared extending from ground over the upper left contact of cam 339, brush 344, commutator segment 345, upper 70 left contact of cam 313 to the fundamental circuit as previously traced. As the district selector moves upward the stepping relay 702 will be periodically shunted and the counting relays operated beginning 75 with the No. 1 counting relay. When the 0' counting relay operates at the second release of relay 702, relay 703 is operated releasing relay 314 and bringing the district selector to rest with its brushes engaging 80 the first terminal of the second group to which the fourth brush set has access.

The release of relay 314 also closes a circuit from battery through the winding of sequence switch magnet 300, right contacts 85 of cam 342, outer left back contact of relay 314 to ground at the back contact of relay 302 advancing the sequence switch to position 7.

In position 7 of sequence switch 300, relay 90 314 is operated in a circuit from battery through its left winding, left contacts of cam 347, contacts of cam 308 back contact of relay 320, line finder commutator segment 321, brush 322 to ground. The operation of relay 314 closes a circuit from battery, through the winding of sequence switch magnet 300, upper left contact of cam 328, left front contact of relay 314, back contact of relay 302 to ground. Sequence switch 300 is advanced in this circuit to position 8.

In position 7 1/4 to 8 relay 314 locks over 95 its inner right front contact, lower contacts of cam 348, to the sleeve brush 349 and ground over the sleeve terminal of the trunk, provided that trunk is busy. The energizing circuit of relay 314 is opened in position 8. If the first trunk of the group is busy and relay 314 is held energized in position 8, a circuit is completed for the updrive magnet 340 from battery, through the winding of the magnet 340, upper right contact of cam 341, left front contact of relay 314 to ground at the back contact of relay 302. The updrive magnet is energized and causes the district selector shaft to move upward in search of an idle outgoing trunk. Relay 314 is held operated between terminals over a circuit extending from battery, through its left winding, upper contacts of cam 347, commutator segment 384, brush 371, lower left contact of cam 341, outer left front contact of relay 314, back contact of relay 302 to ground. As soon as an idle trunk is reached, characterized by the absence of ground on its sleeve terminal, the locking circuit of relay 100 115 120 125 314 is opened and the relay releases in turn

releasing the updrive magnet bringing the district selector to rest on the first idle outgoing trunk of the group. The release of relay 314 closes a circuit from battery, winding of sequence switch magnet 300, right contacts of cam 342, left back contact of relay 314, back contact of relay 302 to ground, advancing the sequence switch to position 9.

10 As soon as relay 314 releases, ground is connected to sleeve terminal 383, over the upper right contact of cam 339, outer right back contact of relay 314, right contacts of cam 350, through sleeve brush 349, to render the selected trunk busy. As soon as the sequence switch arrives in position 8 3/4 ground is connected over the lower left and upper right contacts of cam 350 and sleeve brush 349, to sleeve terminal 383, independent of relay 314, which ground is maintained until the sequence switch leaves position 15 1/4.

With sequence switch 300 in position 9 a circuit is completed from battery through the winding of relay 351 upper left contact of cam 316, conductor 315, to brush 464 and its associated terminal, and thence through the right winding of relay 406, and the winding of relay 407, to brush 484 and its associated contact as previously traced. From brush 484 this circuit is extended over conductor 506, right back contact of relay 505, inner left contact of relay 504, middle and right windings of relay 503 to ground. A parallel circuit is also closed through the right winding of relay 317, left contacts of cam 316 and thence as traced for relay 351 to ground. Relay 351 operates in this circuit, but relay 317 being marginal does not. The operation of relay 351 closes a circuit from battery, through the left winding of relay 314, upper right and lower left contacts of cam 352, left contact of relay 351, line finder commutator segment 353, brush 354 to ground. Relay 314 operates and closes a circuit from battery, through the winding of sequence switch magnet 300, upper left contact of cam 328, left front contact of relay 314, left back contact of relay 302 to ground. Sequence switch 300 is advanced in this circuit to position 10 in which position it remains during subsequent selections.

These subsequent selections take place as described in the above identified application of O. H. Kopp with the exception of the manner of insuring that a coin has been deposited at the calling subscriber's substation before permitting the completion of a connection.

The operation of relay 507 at the time the sender is selected closes a circuit from battery, through the winding of relay 601, right normal contact of relay 601, normal terminal and brush 602 of the timing switch 600,

conductor 534, inner left front contact of relay 507 to ground. Relay 601 in operating closes a circuit from battery, through the winding of relay 603, brush 604 and its normal terminal, inner left front contact of relay 601 to ground. Relay 603 closes a circuit from battery, through the winding of stepping magnet 605, back contact of magnet 605, inner right front contact of relay 603, brush 604 and its normal terminal, inner left front contact of relay 601 to ground. Magnet 605 operates and steps switch 600 to its first off normal position.

With the brushes of switch 600 engaging their first off normal terminals a circuit is completed from battery, through the winding of relay 1205, No. 1 terminal of brush 602, conductor 534 to ground. Relay 1205 operates and locks over its right front contact, outer right contact of relay 1207, outer left back contact of relay 526, inner left back contact of relay 539 to ground over conductor 534.

The operation of relay 1205 closes a circuit from battery, through the winding of relay 603, brush 604, and its No. 1 terminal, left front contact of relay 1205 to ground over conductor 534. Relay 603 operates and causes the operation of magnet 605 to advance switch 600 to its No. 2 position. The stepping magnet 605 is then energized over the contact of interrupter 628, No. 2 and 3 terminals of brush 629, outer right back contact of relay 603 to ground at the right normal contact of relay 1201. Switch 600 is advanced one step each time that interrupter 628 closes its contact and comes to rest in its No. 4 position.

If dialing has not been started at this time, no circuit is closed for advancing this switch to its No. 5 position and the call is directed to the sender monitor operator's position in the manner described in the above identified application of O. H. Kopp.

If dialing has commenced and steering switch 800 has been advanced to its No. 1 position when switch 600 steps to its No. 4 position a circuit is closed from battery through the winding of relay 603, brush 631 and its No. 4 terminal, off normal terminals of brush 805 to ground. Relay 603 operates and causes the operation of stepping magnet 605, advancing switch 600 immediately to its No. 5 position. Switch 600 advances to its No. 7 position under the control of interrupter 628.

If switch 800 has not been advanced to its No. 8 or No. 9 position at this time, a circuit is closed from battery through lamp 632, resistance 633, No. 7 terminal and brush 629, outer right back contact of relay 603, to ground at the back contact of relay 1201, and switch 600 remains in this position. However, if switch 800 is in its No. 8, 9 or 10 position a circuit is closed from battery,

through the winding of relay 603, brush 631 and its No. 5 to 7 terminals, terminals No. 8 to 10 of brush 805 to ground. The operation of relay 603 causes the stepping magnet 605 to step switch 600 to its No. 8 position. Switch 600 is now advanced from the No. 8 to the No. 12 position due to the operation of relay 603 over brush 631, left back contact of relay 634 to ground at the 10 back contact of relay 1201. It then advances to its No. 15 position due to the operation of relay 603 through brush 631 to ground on terminals No. 12 to 14.

When switch 600 reaches its No. 15 position a circuit is completed from battery through the winding of relay 1200, outer left back contact of relay 539, terminal No. 15 and brush 602 to ground over conductor 534. The operation of relay 1200 transfers 20 the tip conductor from ground to the right winding of relay 1206, inner right back contact of relay 1207, right winding of relay 1208, resistances 1209 and 1210, to ground; and the ring conductor from the winding 25 of relay 606 to the left winding of relay 1206, inner left back contact of relay 1207, left winding of relay 1208, resistance 1211, outer right front contact of relay 1200 to battery. The operation of relay 1200 also 30 closes a substitute circuit for relay 606 over the left alternate contact of relay 1200 through resistance 1212 to ground. Relay 1206 operates in the above traced circuit and remains operated during coin test unless the calling subscriber replaces his receiver on the switchhook.

If the subscriber abandons the call at this time relay 1206 releases and connects battery through the 52.5 ohm resistance 905 40 over its left back contact, and outer left front contact of relay 1200 to the winding of relay 606, releasing that relay to permit the restoration of the sender. Relay 1208 tests for the presence of ground at the 45 subscriber's substation. It will be operated by ground through a resistance of 0 to 1000 ohms but will not be operated by a 10,000 ohm leak.

Assuming that a coin has been deposited 50 in coin box 140 relay 1208 will be operated. Relay 1208 locks from battery through the outer right contact of relay 1200, resistance 1211, left winding and contact of relay 1208 to ground on conductor 534 as previously traced.

The operation of relay 1208 closes a circuit from battery over the right contact of relay 1208, winding of relay 1207, left back contact of relay 526, inner left back contact of relay 539, to ground over conductor 534. Relay 1207 operates and transfers the tip and ring conductors from the windings 60 of relay 1208 to the middle and right windings of relay 1213. Relay 1213 is so adjusted as to be operated by direct ground at

the subscriber's substation but is not operated by ground through the windings of the coin magnet, which has a resistance of about 1000 ohms. The operation of relay 1207 also opens the holding circuit of relay 1205 but relay 1205 is slow to release so that relay 1213 has sufficient time to operate and lock before relay 1205 closes its back contact. If, due to a trouble condition or an attempt to obtain a free call, a direct 70 ground is present at the subscriber's substation, relay 1213 operates and is held operated in a circuit from battery, right contact of relay 1208, left winding of relay 1213, outer left back contact of relay 526, 80 inner left back contact of relay 539, to ground at the conductor 534. The operation of relay 1213 connects ground from conductor 534, over the inner left back contact of relay 539, outer left back contact of 85 relay 526, front contact of relay 1213, right front contact of relay 1205, through the winding of relay 1205 to battery, holding that relay operated.

During the above operations switch 600 90 is advanced from position 15 to position 17 due to the closure of a circuit from battery, through the winding of stepping magnet 605, contact of interrupter 628, No. 15 and 16 terminals and brush 629, right back contact 95 of relay 603 to ground at the right normal contact of relay 1201. If relay 1205 is not released when switch 600 reaches its No. 17 position, lamp 650 is lighted in a circuit from battery through lamp 650, No. 17 terminal 100 and brush 629, right back contact of relay 603 to ground at the right normal contact of relay 1201. This lamp is located at an operator's position and the operator, observing the lamp, inserts a plug in jack 1214. Battery on the sleeve of the operator's cord circuit causes the operation of relay 1201 which in turn causes the operation of relay 1204. The operation of relay 1204 extends the tip 110 and ring conductors to the operator's cord so that she may converse with the calling subscriber. The operation of relay 1204 also opens the circuit of relay 1208 and that relay releases. When the operator removes her plug from jack 1214, relays 1201 and 1204 115 release and the conductors are again extended to relay 1208 so that the coin test may be repeated.

If, as assumed, the coin is properly deposited relay 1213 does not operate and when relay 1205 closes its back contact, a circuit is completed from battery through the inner left contact of relay 621, right winding of relay 539, back contact of relay 1205, to ground over conductor 534. Relay 539 operates and opens the circuit of relay 1207, in turn releasing relay 1209. The operation of relay 539 also closes a circuit from battery through the winding of relay 603, brush 631 and its No. 17 terminal, left 120 125 130

front contact of relay 539 to ground over conductor 534. Relay 603 causes the advance of switch 600 to its No. 18 position. As soon as switch 600 leaves its No. 17 terminal relay 539 releases.

When the sender sequence switch arrives in position 13 on its second revolution, preparatory to making final units selection, a circuit is closed from battery through the winding of relay 711, upper contacts of cam 527, outer right back contact of relay 515, lower right contact of cam 727, right contacts of cam 533, left front contact of relay 1205, to ground over conductor 534, provided relay 1205 is still operated.

If relay 1205 is still operated and relay 711 operates, the circuit for advancing sequence switch 700 for final units selection is opened and the completion of a call is prevented. If, as above described, the coin has been properly deposited and relay 1205 released, relay 711 is either not operated at all or released after a short interval and the call is completed as described in the above identified application of O. H. Kopp. Switch 600 is advanced from its No. 18 to 21 position in a circuit from battery through the winding of stepping magnet 605, contact of interrupter 628, terminals No. 18 to 20 and brush 629, right back contact of relay 603 to ground at the right normal contact of relay 1201. If selection has not been completed by the time switch 600 reaches its No. 20 position, a circuit is completed from battery, through the winding of relay 603, brush 631 and its No. 20 terminal, right contact of cam 957 to ground, and relay 603 operates advancing switch 600 immediately to its No. 21 position. As switch 600 enters its No. 21 position, lamp 632 is lighted in a circuit from battery, through the lamp, right back contact of relay 634, contact of interrupter 635, No. 21 terminal of brush 629, right back contact of relay 603 to ground at the right normal contact of relay 1201. Lamp 632 flashes in this circuit indicating to the sender monitor that the selections have not been properly completed.

If selectors have been completed and the sender disconnected, the circuit of relay 601 is opened and that relay releases closing a circuit from battery, through the winding of relay 603, brush 604 and its off normal terminals to ground at the back contact of relay 601 restoring switch 600 to normal. This circuit is completed whenever relay 601 is released. The release of the sender and the link circuit are as described in the above identified application of O. H. Kopp.

Assuming that this is a call for which a charge is to be made, district selector sequence switch 300 will be advanced to position 14 in the manner described in the above identified application of O. H. Kopp.

When the called subscriber answers, relay

361 operates in the well known manner. With sequence switch 300 in position 14 a circuit is completed from battery through the lower left winding of repeating coil 360, upper left contact of cam 329, winding of relay 330, right back contact of relay 325, line finder brush 331, terminal 332, conductor 116, through the subscriber's substation conductor 117, terminal 333, brush 334, outer left back contact of relay 317, upper right contact of cam 335, upper left winding of repeating coil 360 to ground, in which circuit relay 330 operates.

The operation of relay 361 closes a circuit from battery through the winding of relay 302, contact of interrupter 362, lower contacts of cam 347, front contact of relay 361, left contacts of cam 350 to ground. Relay 302 operates and locks over its inner right contact, lower right contact of cam 308, front contact of relay 361, left contacts of cam 350 to ground. Relay 302 closes a circuit from battery, through the winding of relay 359, contact of interrupter 363, upper right contact of cam 364, outer left front contact of relay 302 to ground. Relay 359 operates and locks in a circuit through its inner right contact, lower left contact of cam 336 to ground. The operation of relay 359 closes a circuit from battery through resistance 365, outer left front contact of relay 359, lower left and upper right contacts of cam 318, to a terminal in the arc served by brush 1301 of switch 1300.

When conversation is completed, and the calling and called subscribers hang up, relay 330 is released. The release of relay 330 closes a circuit from battery, through the winding of relay 351, contact of relay 330, upper contact of interrupter 367, upper left contact of cam 336 to ground. Relay 351 operates as soon as interrupter 367 closes its contact and locks in a circuit over the back contact of relay 330, left contacts of cam 352, left front contact of relay 351, commutator segment 353, brush 354 to ground. The operation of relay 351 closes a circuit from battery through the right winding of relay 317, right front contact of relay 351, lower contact of interrupter 367, upper left contact of cam 336 to ground. Relay 317 operates as soon as interrupter 367 closes its lower contact, and locks in a circuit through its left winding and inner left front contact, upper right contact of cam 336 to ground. The operation of relay 317 transfers the tip and ring leads from the repeating coil to terminals served by brushes 1303 and 1304 of switch 1300. The operation of relay 317 also closes a circuit from ground over the upper right contact of cam 336, inner left front contact of relay 317, left normal contact of relay 387, winding of relay 388, to battery. Relay 388 operates and connects ground over its inner right

front contact, through the winding of relay 389 to a terminal served by brush 1305. The operation of relay 388 also connects battery, through resistance 390, inner right front contact of relay 388, right back contact of relay 389 to a terminal in the arc served by brush 1306. It also closes a circuit from ground at the back contact of relay 389, outer right front contact of relay 388, windings of the start relay of all coin circuits, in this case relay 1310.

Relay 1310 operates and connects ground over its contact, contact 1311 of make busy jack 1312, back contact of relay 1313, outer left back contact of relay 1314, winding of magnet 1307, to battery. Magnet 1307 operates and close an obvious circuit for magnet 1308 which magnet causes switch 1300 to rotate in search of the terminal to which battery has been connected from the front contact of relay 388. All idle coin circuits such as shown in Fig. 13 are started in search of district selectors shown in Fig. 3. Busy coin circuits have the above traced circuit for magnet 1307 opened at the contact of relay 1314 and hence are not moved out of their rest positions.

When switch 1300 encounters the terminal connected to battery, a circuit is completed from battery through resistance 390, inner left front contact of relay 388, right back contact of relay 389, terminal served by brush 1306, contact 1315 of jack 1312, winding of relay 1313, both the windings of relay 1316 to ground. Relay 1316 operates in this circuit and closes a shunt around its high resistance winding, reducing the resistance of the circuit sufficiently to permit the operation of relay 1313. The operation of relay 1313 opens the circuit of magnet 1307, in turn releasing magnet 1308 and bringing switch 1300 to rest in connection with the district selector of Fig. 3. A circuit is also completed from battery, through the winding of relay 1314, brush 1305 and its corresponding contact, winding of relay 389, inner right front contact of relay 388 to ground. Relays 1314 and 389 both operate in this circuit. The operation of relay 389 removes ground from relay 1310, thus stopping all the other coin circuits as well.

The operation of relay 1314 opens the circuit of magnet 1307 at a second point to insure that switch 1300 will not be moved while in use. The operation of relay 389 removes battery from the terminals of other coin circuit switches to prevent the connection of a second coin circuit with this district. The operation of relay 1314 also extends the circuit prepared from battery through resistance 365 over the outer left front contact of relay 359, lower left and upper right contacts of cam 318, terminal of brush 1301 over the inner left front contact of relay 1314, right winding of relay 1325 to ground.

Relay 1325 operates and locks in a circuit from battery through its left winding and inner left alternate contact to the ground at the outer left front contact of relay 1314.

The operation of relay 1314 also closes a circuit from battery, through the left winding of relay 1317, winding of relay 1318, left back contact of relay 1317, outer right back contact of relay 1319, contact of interrupter 1320, outer right front contact of relay 1314 to ground. Relay 1318 operates when interrupter 1320 closes its contact, but relay 1317 does not being marginal. Relay 1318 in operating closes a locking circuit for itself from battery through the left winding of relay 1317, winding of relay 1318, right winding of relay 1317, inner left front contact of relay 1318 to ground at the outer right front contact of relay 1314. Relay 1317 does not operate in this circuit since its right winding is shunted by the energizing circuit of relay 1318. The operation of relay 1318 also closes a circuit from battery through the winding of relay 1321, inner right front contact of relay 1318, left back contact of relay 1322, left normal contact of relay 1323, left normal contact of relay 1319 to ground at the outer right front contact of relay 1314. Relay 1321 operates and locks over its inner left front contact, left back contact of relay 1322 and thence to ground as over the energizing circuit. The operation of relay 1321 closes a circuit from battery through the winding of relay 1324, inner right front contact of relay 1321 to ground. The operation of relay 1324 connects the tip and ring conductors together and connects them to the outer right front contact of relay 1317. When interrupter 1320 opens its contact it opens the energizing circuit of relay 1318 and permits relay 1317 to operate in the locking circuit of relay 1318. The operation of relay 1317 extends the tip and ring conductors over its outer right front contact, through the winding of relay 1326, outer right front contact of relay 1325, through lamp 1327 to 110 volt positive coin battery. Relay 1326 operates in this circuit and closes an obvious circuit for relay 1322. Relay 1322 locks in a circuit from battery through its winding and inner right front contact, left normal contact of relay 1323, left normal contact of relay 1319, outer right front contact of relay 1314 to ground. The operation of relay 1322 opens the locking circuit of relay 1321.

When interrupter 1320 next closes its contact it connects ground from the outer right front contact of relay 1314, over its contact, outer right back contact of relay 1319, left front contact and left winding of relay 1317 to battery. This circuit shunts relay 1318 but holds relay 1317 operated.

When interrupter 1320 again opens its contact relay 1317 releases opening the ener-

- gizing circuit of relay 1321. With relay 1322 operated and relays 1318, 1317 and 1321 released, a circuit is completed from battery through the winding of relay 1328, 5 outer left front contact of relay 1322, outer right back contact of relay 1321, outer right back contact of relay 1318, inner right back contact of relay 1317, left normal contact of relay 1323, left normal contact of relay 1319, outer right front contact of relay 1314 to ground. Relay 1328 operates and locks over its right contacts over the left normal contacts of relays 1323 and 1319 to ground at the outer right front contact of relay 1314. 10 When interrupter 1320 again closes its contact, the previously traced circuit for relay 1318 extending through the left winding of relay 1317 is closed. Relay 1318 operates in turn operating relays 1321 and 1324 but 15 relay 1317 does not operate. When interrupter 1320 opens its contact, relay 1317 operates as before described. The operation of relay 1317 again closes 110 volt battery through lamp 1327, outer right 20 front contact of relay 1325, winding of relay 1326, outer right front contact of relay 1317, over the front contacts of relay 1324 to the tip and ring conductors for test purposes. If the coin has been collected 25 ground is removed from the tip and ring conductors and the circuit of relay 1326 is not completed. When interrupter 1320 next closes its contact, it shunts relay 1318 releasing it, but relay 1321 is held locked over the right contact of relay 1328 right normal contacts of relays 1323 and 1319 to ground at the outer right front contact of relay 1314. When 30 interrupter 1320 next opens its contact relay 1317 also releases. With relays 1317 and 1318 released and relays 1321 and 1322 operated, a circuit is closed from battery, through the left winding of relay 1323, middle right back contact of relay 1319, 35 outer right front contact of relay 1322, outer right front contact of relay 1321, right back contact of relay 1318, inner right back contact of relay 1317, left normal contact of relay 1323, left normal contact of relay 1319, outer right front contact of relay 1314 to ground. Relay 1323 operates and locks over its left alternate contact, left normal contact of relay 1319 to ground 40 at the outer right front contact of relay 1314. The operation of relay 1323 opens the locking circuit of relays 1322, 1328, and 1321. The release of relay 1321 permits the release 45 of relay 1324. When relay 1323 operates a circuit is closed from battery through the right winding of relay 387, terminal served by brush 1302, inner right front contact of relay 1323, left normal contact of relay 1319, outer right front contact of relay 1314 to ground. The operation of relay 387 opens 50 the circuit of relay 388 permitting that re- lay to release. The release of relay 388 opens the circuit of relay 1314, opening the locking circuit of relay 1323, restoring the coin circuit to normal. The brushes of switch 1300 remains in engagement with 55 this district selector until moved therefrom in connection with another call. When relay 389 was operated at the time that the coin circuit hunting switch found the district in Fig. 3, a circuit was completed 60 from battery, through the winding of sequence switch magnet 300, lower right and upper left contacts of cam 301, left front contact of relay 389 to ground. Sequence switch 300 advanced to position 17 in this 65 circuit. As sequence switch 300 passes through position 16 the circuit of relay 351 is opened and that relay releases. When sequence switch 300 reaches position 17 a circuit is 70 again completed for operating relay 351 which may be traced from battery, through the winding of relay 351, back contact of relay 330, contact of interrupter 367, upper left contact of cam 336 to ground. Relay 75 351 operates and locks over the back contact of relay 330, left contacts of cam 352, left front contact of relay 351 to ground on commutator segment 353. When relay 387 80 operates after the coin circuit has functioned the reduced battery potential for marking line 100 busy is removed from brush 326 and a circuit is completed from battery, through the winding of relay 302, lower contacts of cam 368, inner right front contact of relay 85 387 to ground. Relay 302 operates and locks over its inner right front contact, upper contact of relay 308, to ground on commutator segment 353. The operation of relay 302 closes a circuit from battery through 90 the winding of sequence switch magnet 300, upper left contact of cam 311, outer left front contact of relay 302 to ground, advancing sequence switch 300 to position 18. With relay 302 operated and sequence switch 95 300 in position 18, a circuit is completed from battery, winding of down drive magnet 372, lower left contact of cam 364, outer left front contact of relay 302 to ground, and the line finder is restored to normal 100 under the control of down drive magnet 372. When the line finder reaches normal the brush 354 no longer engages commutator segment 353 and relays 302 and 351 are 105 released. The release of relay 302 opens the 110 circuit of line finder down drive magnet 372. A circuit is also completed in position 18 of sequence switch 300 from battery, through the winding of down drive magnet 369, upper right and lower left contacts of cam 313, 115 lower contacts of cam 350 to ground. The district selector is restored to normal under control of magnet 369. When the district selector reaches normal a circuit is completed from battery through the winding of 120 125 130

- sequence switch 300, upper right contact of cam 328, commutator segment 370, brush 371, upper left contact of cam 339, to ground, advancing sequence switch 300 to position 1. When sequence switch 300 arrives in position 1, battery through the 150 ohms of resistance 323 is connected over the outer right back contact of relay 302, upper left and lower right contact of cam 324, contacts 395 of jack 374, conductor 366 to the multiple terminal appearing in district finder switches such as switch 460, to indicate to idle link circuits that this line finder-district selector unit is ready for use.
- 18 If the called subscriber's line is busy, or if the called subscriber does not answer relay 361 is not operated and relays 302 and 359 are not operated. When the calling subscriber's circuit is opened, relay 330 releases and relay 351 operates and locks as described. The operation of relay 351 causes the operation of relay 317 and extends the tip and ring conductors to the coin circuit. The operation of relay 317 causes the operation of relay 388 and the association of a coin circuit with the district selector to refund the coin deposited at the subscriber's substation. Since relay 359 is not operated, battery is not connected to the terminal of brush 301, and relay 1325 is not operated and negative battery is applied to the calling subscriber's line to cause the refund of the coin. The restoration of the district selector is the same as described.
- 35 In the case of free calls district selector 300 is brought to rest in position 13 and no circuit is prepared for relay 1325 of the coin circuit. In this case with relays 1324 and 1317 operated, the tip and ring conductors are extended over the front contacts of relay 1324, outer right front contact of relay 1317, through relay 1326, outer right back contact of relay 1325, outer left front contact of relay 1321 through lamp 1330 to source of 110 volt negative battery. This causes the magnets of coin box 140 to refund the coin.
- 50 In the case of calls to an operator, sequence switch 300 is brought to rest in position 15. The circuit from battery through resistance 365 over the contact of relay 359 is open at the lower left contact of cam 318 with the sequence switch in this position, relay 1325 is not operated, and the coin deposited in coin box 140 is returned. When the operator answers, relay 361 operates as in the case of a called subscriber. The operation of relay 361 closes a circuit from battery, through the left winding of relay 314, left contacts of cam 347, front contact of relay 361, left contacts of cam 350 to ground. Relay 314 operates and locks through its right winding and outer right contact, right contacts of cam 350, to ground 65 on the sleeve of the operator's trunk. The operation of relay 314 closes a circuit from battery, winding of sequence switch magnet 300, upper left contact of cam 328, left front contact of relay 314, lower left contact of cam 339 to ground advancing sequence switch 300 to position 16.
- 70 In position 16 the talking circuit is extended from the operator's position over brush 357, upper left contact of cam 335, left back contact of relay 317, line finder brush 334 and thence over the subscriber's line back to brush 331, right back contact of relay 317, winding of relay 380, lower right contact of cam 329, brush 355 and back to the operator's trunk. The talking circuit is thus independent of the repeating coil and supervisory relay 361 when talking to an operator. When the operator disconnects, relay 314 releases and closes a circuit from battery, winding of sequence switch magnet 300, right contacts of cam 342, left back contact of relay 314, lower left contact of cam 339 to ground, advancing the sequence switch to position 17.
- 75 The selection of the district selector by a coin circuit and the restoration of the coin circuit and district selector take place as previously described.
- 80 If a call is abandoned before the deposit of a coin, the coin circuit of Fig. 13 selects the district but since no coin is present relay 1326 is not operated on the first application of coin battery and hence relay 1322 is not operated and the second cycle of operations involving relays 1317, 1318, etc., does not take place. Relay 1323 is operated at the first release of relays 1317 and 1318 and relay 387 of the district is operated to bring about the release of the coin circuit and the district selector.
- 85 The selection of the district selector by a coin circuit and the restoration of the coin circuit and district selector take place as previously described.
- 90 If a call is abandoned before the deposit of a coin, the coin circuit of Fig. 13 selects the district but since no coin is present relay 1326 is not operated on the first application of coin battery and hence relay 1322 is not operated and the second cycle of operations involving relays 1317, 1318, etc., does not take place. Relay 1323 is operated at the first release of relays 1317 and 1318 and relay 387 of the district is operated to bring about the release of the coin circuit and the district selector.
- 95 If the coin is not collected or refunded at the first application of coin battery as above described, relay 1326 is operated a second time and a circuit is closed from battery through the winding of relay 1319, outer left front contact of relay 1328, inner right front contact of relay 1326 to ground. Relay 1319 operates and locks over its left front contact to the outer right front contact of relay 1314. The operation of relay 1319 closes a circuit from battery, through lamp 1331 at the monitoring operator's position over the right back contact of relay 1323, inner right front contact of relay 1319 and thence over the outer left front contact of relay 1318 to ground at the outer right front contact of relay 1314, or over the inner left back contact of relay 1325 and through the upper left contact of relay 1314 to ground, depending upon whether the coin should be collected or refunded. It will be noted that if the coin should have been collected relay 1325 will be operated and the continued presence of the coin will cause the repeated

operation and deenergization of relay 1318. The lamp 1331 will flash.

When the monitoring operator observes this signal she inserts her plug into jack 1332 whereupon battery from the sleeve of her cord will cause the operation of relay 1323, retiring lamp 1331. The operator then attempts to return or collect the coin with the means provided at her position. The 10 coin circuit is subsequently released by the maintenance force.

The coin circuit is associated with the district in connection with every call, it being necessary to do so in order to release the 15 district.

What is claimed is:

1. In a telephone exchange system, a calling line, a service charging device on said calling line, means for extending said calling line, a plurality of control devices, means to cause all idle control devices to hunt for said extended calling line, means for arresting all of said control devices when one of said control devices is connected with said 25 extended line and means in said control device for operating said service charging device.

2. In a telephone exchange system, a calling line, a service charging device on said calling line, a selector switch for extending connections from said calling line, a plurality of central office devices for controlling said charging device, means at said selector switch for causing all idle control devices 35 to hunt for said selector switch and means for arresting all of said control devices when one of said devices has found said selector switch.

3. In a telephone exchange system, a calling line, a service charging device on said calling line, a selector switch for extending said calling line, a plurality of control devices, a hunting switch for each of said control devices, means at said selector switch 40 for starting the hunting switches associated with all idle control devices in search of said selector switch and means at each of said control devices for arresting the movement of said hunting switches when one of said switches finds said selector switch.

4. In a telephone exchange system, a calling line, a service charging device on said calling line, a selector switch for extending connections from said calling line, a plurality of variably operable control devices, means at said selector switch for causing one 45 of said control devices to connect with said selector switch and means in said selector switch for varying the operation of said control device to variably control the operation of said service charging device.

5. In a telephone exchange system, a calling line, a service charging device on said calling line, a selector switch for extending said calling line, a plurality of control de-

vices, means responsive to the termination of a connection at said calling line to cause an idle one of said control devices to associate itself with said selector switch to operate said service charging device and means 70 for releasing said selector switch dependent upon the correct functioning of said control device.

6. In a telephone exchange system, a calling line, a service charging device on said calling line, a selector switch for extending connections from said calling line, a plurality of control devices, means at said selector switch for causing one of said control devices to connect with said selector switch, a plurality of relays in said control device, means for causing said relays to perform a cycle of operations to control said service charging device, and means responsive 75 to the presence of a coin at said charging device to cause said relays to repeat their cycle of operation.

7. In a telephone exchange system, a calling line, a service charging device on said calling line, a selector switch for extending connections from said calling line, a plurality of control devices, means at said selector switch for causing one of said control devices to connect with said selector switch, a plurality of relays in said control device, means for causing said relays to perform a cycle of operations to control said service charging device, means responsive to the presence of a coin at said charging device 90 to cause said relays to repeat their cycle of operation to test whether said coin is still present at said charging device, and means responsive to the absence of said coin to cause said control device to be restored to 95 normal and to restore said selector switch.

8. In a telephone exchange system, a calling line, a service charging device on said calling line, a selector switch for extending connections from said calling line, a plurality of control devices, means at said selector switch for causing one of said control devices to connect with said selector switch, a plurality of relays in said control device, means for causing said relays to perform a cycle of operations to control said service charging device, means responsive to the presence of a coin at said charging device to cause said relays to repeat their cycle of operation to test whether said coin is still present at said charging device, and means responsive to the continued presence of said coin to display a signal.

9. In a telephone exchange system, a calling line, a service charging device on said calling line, a plurality of selector switches for extending said calling line to a called line, a plurality of register senders, means for associating one of said register senders with the first of said selector switches, means in said register sender for testing for 110 115 120 125 130

the presence of a coin at said service charging device to permit the completion of the connection between said calling line and said called line, a plurality of coin control devices, means responsive to the termination of the call at said calling line for causing one of said control devices to associate itself with said first selector switch and means in said control device for causing the operation of said service charging means.

10. In a telephone exchange system, a calling line, a coin device on said calling line, a selector switch for extending said calling line, a plurality of register senders, means for associating one of said register senders with said selector switch, means in said register sender for testing for the presence of a coin at said coin device, a plurality of coin control devices, means responsive to the termination of a call at said calling line, to cause one of said coin control devices to associate itself with said selector switch and means in said control device to dispose of said coin and to release said selector switch.

11. In a telephone exchange system, a calling line, a service charging device on said calling line, a plurality of selector switches for extending said calling line to a called line, a plurality of register senders for controlling such extension, means for associating one of said register senders with the first of said selector switches, means in said register sender for testing for the presence of a coin at said service charging device to permit the complete extension of said calling line to said called line, a plu-

rality of variably operable coin control devices, means at said selector switch responsive to the termination of a call at said calling line, for causing one of said control devices to associate itself with said first selector switch and means in said selector switch to determine the operation of said control device to variably operate said service charging device.

12. In a telephone exchange system, a calling line, a service charging device on said calling line, a plurality of selector switches for connecting said calling line with a called line, a plurality of register senders for controlling said connection, means for associating one of said register senders with the first of said selector switches, means in said register sender for testing for the presence of a coin at said service charging device to permit the completion of said connection, a plurality of variably operable coin control devices, means at said selector switch, responsive to the termination of a call at said calling line, for causing one of said control devices to associate itself with said first selector switch, and means in said selector switch for causing the variable operation of said coin control device to cause said service charging device to collect or refund said coin according to whether or not the connection was completed.

In witness whereof, I hereunto subscribe my name this 2nd day of October A. D., 1924.

ISRAEL H. HENRY.
